CLAIM

We claim the ornamental design for a display screen with graphical user interface for a prompt animation, as shown and described.

DESCRIPTION

This application is related to co-pending U.S. Design application Ser. No. 29/586,422 entitled "Graphical User Interface of a Prompt Animation for a Display Screen," filed on an even date herewith.

FIG. 1 is a view of a first image of a display screen with graphical user interface for a prompt animation.

FIG. 2 is a view of a second image thereof.

FIG. 3 is a view of a third image thereof.

FIG. 4 is a view of a fourth image thereof.

FIG. 5 is a view of a fifth image thereof.

FIG. 6 is a view of a sixth image thereof; and,

FIG. 7 is a view of a seventh image thereof.

The broken lines shown in the figures illustrate portions of the graphical user interface and display screen that form no part of the claimed design.

The appearance of the design transitions sequentially between the images shown in FIGS. 1-7. The process or period in which one image transitions to another forms no part of the claimed design.
